T. F. ALLEN.
CAR TRUCK.

No. 27,608.

Patented Mar. 27, 1860.

UNITED STATES PATENT OFFICE.

T. F. ALLEN, OF DYERSVILLE, IOWA.

BRACKET FOR RAILROAD-CAR TRUCKS.

Specification of Letters Patent No. 27,608, dated March 27, 1860.

To all whom it may concern:

Be it known that I, T. F. ALLEN, of Dyersville, in the county of Dubuque and State of Iowa, have invented a new and useful Improvement in Suspension-Brackets of Railroad-Car Trucks; and I do hereby declare that the following is a full, clear, and exact description of the same, reference being had to the accompanying drawings, forming a part of this specification, in which—

Figure 1, is a transverse view of a railroad car truck having my improvement applied to it; the section being taken in the line x, x , of Fig. 2. Fig. 2, is a vertical longitudinal section of the same in the line y, y , of Fig. 1. Fig. 3, is a side elevation of my improved suspension bracket detached from the truck but resting in its horizontal bearing plate.

Similar letters of reference, in each of the several Figures indicate corresponding parts.

The nature of my invention consists in a suspension bracket which is capable of changing its bearing point and which acts by reason of changing its point of bearing with a counteracting force against the lateral vibrations of the car body thus checks to a considerable extent, the preponderance of weight on either side of the track-frame and preventing much of the injurious effect which the journal or side springs usually encounter when brackets which have fixed fulcra are used.

To enable others, skilled in the art, to make and use my invention, I will proceed to describe its construction and operation.

In the drawing, I have shown a car-truck having its swinging beam constructed according to my patent dated March 29, 1859, but I wish it to be distinctly understood that I do not limit the use of my present invention to this character of swinging beam.

A, in the drawing, represents the swinging beam provided with a central bearing B, to receive the king bolt which fastens the car-body to the truck. This swinging beam I suspend on the truck-frame C, in the following manner.

Near each end of the beam, on both sides, I provide swinging brackets D, D, these brackets are hinged at their lower ends to fulcrum rods a, a , which attach to the under-

side of the spring supporting plate, as shown.

The upper ends of the brackets extend up through flaring slots b, b , cut in the transverse timbers of the truck frame and in the bearing plates c, c , which are bolted to the top of said timbers. It will be observed that the tops d , of the brackets are enlarged to a considerable extent and that the underside of said enlargements have the form of a segment of a circle. Thus enlarging and curving the brackets and having the curved portion roll on the horizontal bearing plates enables me to accomplish the object heretofore named, to wit, having the brackets to act with a counteracting force against the lateral vibrations of the car body; for it will be seen whenever the car-body swings to the right the lower end of the brackets will be thrown in the same direction that the car swings, while the upper curved bearing portions swing to having no fixed fulcra are moved in a reverse direction and consequently caused to bear upon the plates on one side at points nearer the center of the truck frame and on the other side at points farther from the center and thus act with a counteracting force sufficient to check or equalize to a considerable extent the preponderance of weight which usually comes upon the journal or side springs of the truck when fixed fulcra are employed. The result is just the same whenever the car swings to the left. Thus it will be seen that the resistance or counteracting force in either direction is always commensurate with the force with which the car-body moves to the right or left, that is if the diameter of the circle which forms the bearing of the swinging brackets is equal to the diameter of the circle described by the lower end of the bracket.

As the car-body is suspended on a swinging beam, and the swinging beam is suspended on the brackets, any motion laterally, of the car-body will be thrown upon the brackets and as the heads of the brackets shift their bearings as described, to an extent commensurate with the extent of the outward movement of the lower ends of the brackets, there is of necessity a leverage or resisting action derived from the bearing points of the brackets, and said action by coming upon the truck has a positive tendency to throw the car-body and swinging beam to an opposite position to that in which

they are moving and thus it is that the preponderance of weight upon the side springs is equalized.

What I claim as my invention and desire to secure by Letters Patent, is—
A suspension bracket D, which is capable of changing its bearing point and which acts, by reason of changing its point

of bearing with a counteracting force against the lateral vibrations of the car body, substantially as and for the purposes set forth.
